UNITED STATES PATENT OFFICE.

MORTIMER C. PARK, OF PLATTE CITY, MISSOURI.

COMBINED GASOLENE BLOWPIPE AND BURNER.

SPECIFICATION forming part of Letters Patent No. 596,536, dated January 4, 1898.

Application filed June 29, 1897. Serial No. 642,873. (No model.)

To all whom it may concern:

Be it known that I, MORTIMER C. PARK, of Platte City, Platte county, Missouri, have invented certain new and useful Improvements 5 in a Combined Gasolene Blowpipe and Burner, of which the following is a full, clear, and exact description, reference being had to the accompanying drawings, forming a part thereof.

My invention relates to combined gasolene 10 blowpipes and burners; and my object is to produce a device of this character whereby a most intense heat may be generated at a minimum of cost and a flame produced which is under perfect control, as regards its volume 15 and formation, of the operator.

A further object is to produce a device of this character which is simple, durable, and cheap of manufacture.

With these objects in view the invention 20 consists in certain novel and peculiar features of construction and combinations of parts, as will be hereinafter described and claimed.

In order that the invention may be fully understood, I will proceed to describe it with 25 reference to the accompanying drawings, in which—

Figure 1 represents a top plan view of a combined blowpipe and burner embodying 30 my invention. Fig. 2 represents a vertical cross-section of the same. Fig. 3 represents a horizontal section of the fuel-reservoir in an inverted position. Fig. 4 represents, on an enlarged scale, detail perspective views of parts of the burner. Fig. 5 represents, on 35 the same scale, a longitudinal section of the burner.

In said drawings, 1 designates a reservoir or tank, preferably of cylindrical form and mounted upon an enlarged base 2, said base 40 preferably forming the bottom of the tank also. Communicating with the tank at its upper end is a filling-tube 3, and closing the same is a removable cap 4, which may be screwed thereon or otherwise secured. The 45 top plate and base-plate of the reservoir or tank are tied together, preferably, by means of vertical rods 5, engaged at their upper ends by clamping-nuts 6. Projecting vertically upward from and communicating with 50 the reservoir is a tube or pipe 7, and the passage of said pipe is controlled by an ordinary gas-burner valve 8, provided with a thumb-

piece or handle 9. A burner 10 of the type shown or of any other preferred construction is mounted upon said tube or pipe, though, 55 if preferred, (and it undoubtedly will be desirable in some connections,) I may connect said burner or its equivalent with the tube 7 by means of a flexible tube, (not shown,) a bent metal tube, or a folding tube or arm, so 60 as to dispose the burner at a point more remote from the tank. I have found in practice, however, that there is not the slightest danger involved in disposing the burner in the position shown. 65

11 designates a pipe which extends down into the reservoir and terminates in a coil or air-distributer of many convolutions, as at 12. Said air-distributer is located in a horizontal plane, preferably, and very near the bottom 70 of the reservoir and is provided in its under side with a large number of perforations 13, from which the air must escape vertically upward, and consequently permeate the entire body of the liquid, so as to give the device a 75 high generating power or large gas-generating capacity in proportion to its size. The air as it rises to the surface of the gasoline, which is the oil preferably used, is completely saturated and occupies the chamber formed 80 above the surface of said oil—viz., the vapor-chamber. The opposite end of the pipe 11 is connected to an air-supply (not shown) through the medium of the flexible tube 14, and mounted upon said pipe 11 and supported, 85 preferably, by an extension of the top plate is a valve 15, provided with a handle 16 of the type shown or any other preferred type.

To withdraw the gases from the tank, I employ a pipe 17, which projects downward only 90 a slight distance through the top of the reservoir. The valve 18 is mounted upon said pipe and is provided with a handle 19.

Connecting the pipes 11 and 17 outward of the valves 15 and 18, respectively, is a cross-pipe 20, provided with a valve 21, having a handle 22, and connected to the outer end of the pipe 17 is a flexible tube 23, which carries at its outer end a burner of my improved construction. This burner comprises a short pipe 100 24, which diminishes toward its discharge end to form a nozzle 25 and at such end is externally screw-threaded to receive a disk 26, forming, preferably, the front closed end of

a cylinder 27, the rear end of which is also closed. Said cylinder 27, at its rear end, is preferably screwed upon the pipe 24, as shown at 28, and within said cylinder said pipe 24 is 5 provided with one or more perforations 29, for a purpose which will be presently explained. At its front end and at various points the cylinder is formed with slots or small openings 30, and screwed upon the front end of the 10 cylinder 27 is a cap 31, provided at its end with an opening 32, in diameter less than the cylinder 27 or the circular series of slots or openings formed therein. This cap is adjustable upon the cylinder in order to equalize 15 the escape of gas from the periphery or outer circle with that escaping from the central tube or pipe, as it will not burn properly without its proper adjustment. A vertically-adjustable rod 35 is provided at its upper end with 20 an angle-arm terminating in a ring 36, in which a soldering-receptacle 37 is removably suspended, said soldering-receptacle being provided, preferably, with a detachable grate 38.

25 In practice when a dentist, for instance, desires to melt solder or any other metal he places the receptacle in which it is contained upon the grate 38 and swings the latter around over the burner 10. He then opens the valve 30 15 in the desired degree and the valve 8 and ignites the gas as it escapes from the burner 10. By this means, owing to the fact that the receptacle 37 has an opening in its bottom, the flame quickly reduces the solder if it is 35 a metal which flows easily. If a harder metal, such as gold, it will be necessary to employ the other burner also, and then he opens valve 18 and ignites the gas as it escapes from 40 said burner. The gas escapes from the nozzle 25 in a thin direct, but invisible, stream and also through the surrounding circle of slots or openings 31 from the cylinder 27, to 45 which it has access through the opening or openings 29. As such gas escapes through said circle of openings it is deflected downwardly and inwardly toward the central stream, escaping from the nozzle by reason of the fact that the opening 32 is of smaller diameter than the circle of slots or openings 30.

50 To control the combustion at the burner, the valve 21 is provided, and under the proper manipulation of the lever 22 the flame escaping from said burner, and which of course is conical in form, may be tapered or elongated 55 more or less. The more air that is permitted to pass through the pipe 20 the more attenuated or pointed the conical flame becomes, and the heat is intensified in a corresponding degree. The greater volume of air from the 60 reservoir does not unduly discharge the gas, because the pressure of air taking a cross-cut through the pipe 20 "backs" the gas and thereby equalizes the pressure. In other words, the burner performs its function properly and consumes the entire volume of inflammable vapor or gas escaping therefrom 65 irrespective of the pressure of the air-supply,

owing to the fact that as the pressure of the air-supply is increased the valve 21 will be opened wider and the air passing through the cross-pipe, as explained, tends to resist the discharge through the pipe 17, and consequently equalizes the pressure of the gas. It will be noted in this connection that without the opening or openings in the pipe 24 and the outlet of the gas or vapor which passes through said openings into the cylinder 27 the burner would not operate. In fact, when the gas is discharged from the nozzle 25 alone the flame of a lighted match held at such point is instantly extinguished; but when the air escapes also in a uniform volume externally of the nozzle a perfect combustion takes place, and the flame, as hereinbefore stated, may be intensified by its proper regulation; but if the amount of air passing through the cross-pipe by means of valve 21 be increased beyond the proper amount necessary to make the hottest flame it will prevent a sufficient quantity of vapor escaping from the reservoir and stop combustion. The necessary amount of air is regulated by the temperature of the room or place where the burner is located to some extent.

This burner is designed particularly for 95 dentists who practice in small towns not provided with gas-works or in the country and who have heretofore been at a disadvantage in economically and expeditiously performing work which requires intense heat.

100 From the above description it will be apparent that I have produced a combined gasoline blowpipe and burner which embodies the features of advantage enumerated in the statement of invention, and it is to be understood that I reserve the right to make such changes as practical experience may dictate which are not a departure from the spirit and scope of the invention.

Having thus described the invention, what 110 I claim as new, and desire to secure by Letters Patent, is—

1. A combined gasoline blowpipe and burner, comprising a reservoir, an air-supply pipe communicating therewith, an air-distributor located in the bottom of the reservoir and communicating with the air-supply pipe, a valve controlling the air-supply pipe, a valve-controlled outlet-pipe communicating with the vapor-chamber of the reservoir, a burner, a flexible pipe connecting the burner and said outlet-pipe, a valve-controlled burner projecting from the top of the reservoir, and a swinging arm provided with a receptacle to contain the articles which are 120 to be subjected to the action of the burners, substantially as described.

2. A combined gasoline blowpipe and burner, comprising a reservoir, an air-supply pipe communicating therewith, an air-distributor located in the bottom of the reservoir and communicating with the air-supply pipe, a valve controlling the air-supply pipe, a valve-controlled outlet-pipe commu-

nicating with the vapor-chamber of the reservoir, a burner, a flexible pipe connecting the burner and said outlet-pipe, a valve-controlled pipe connecting the air-supply pipe and the outlet-pipe outward of their valves, a valve-controlled burner projecting from the top of the reservoir, and a swinging arm provided with a receptacle to contain the articles which are to be subjected to the action of the burners, substantially as described.

3. In a combined gasolene blowpipe and burner, the combination of a suitable reservoir, a valve-controlled air-pipe, communicating therewith and terminating at its lower end at the bottom of the reservoir in a horizontal coil perforated in its underside, a valve-controlled pipe communicating with the upper end of the reservoir, a burner connected with said pipe, and a valve-controlled cross-pipe connecting the supply and outlet pipes outward of their valves, substantially as described.

4. In a combined gasolene blowpipe and burner, the combination of a suitable reservoir provided with a valve-controlled air-supply pipe, an air-distributer within and submerged in the liquid of the reservoir and connected to the supply-pipe, a valve-controlled outlet-pipe, a valve-controlled cross-pipe connecting the supply and outlet pipes, a burner

connected to the outlet-pipe, and comprising a perforated nozzle, a cylinder inclosing the perforated portion of the nozzle and provided with an opening in its front end to receive the point of the nozzle and with openings surrounding the same, and a cap mounted upon the cylinder at its front end, and provided with an opening through which the air from the nozzle and the cylinder may escape, substantially as described.

5. In a combined gasolene blowpipe and burner, the combination with a suitable gas-supply, of a burner comprising a perforated nozzle, a cylinder mounted upon and inclosing that portion of the nozzle provided with the perforations and provided with a central opening to receive the point of the nozzle, and with a surrounding circular series of slots or openings at its front end, and a cap mounted upon the front end of the cylinder and provided with an opening in diameter less than the circle described by said slots or openings, substantially as and for the purpose set forth.

In testimony whereof I affix my signature in the presence of two witnesses.
